(57) **CLAIM**

The ornamental design for a display adapter, as shown and described.

DESCRIPTION

FIG. 1 is a perspective view of a display adapter showing our new design in a first, closed state;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a display adapter showing our new design in a second, open state;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view of a display adapter showing a second embodiment of our new design from FIGS. 1 through 8;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The broken line showing of various features of the display adapter in the figures is for environmental purposes and forms no part of the claimed design.
